[57] **CLAIM**

The ornamental design for an electronic memorandum
input/output terminal, as shown and described.

DESCRIPTION

FIG. 1 is a top plan view of an electronic memorandum
input/output terminal showing our new design with the
cover dosed;

FIG. 2 is a front elevational view thereof;

FIG. 3 is a right side elevational view thereof;

FIG. 4 is a bottom plan view thereof;

FIG. 5 is a rear elevational view thereof;

FIG. 6 is a left side elevational view thereof;

FIG. 7 is a top plan view thereof with the cover open;

FIG. 8 is a front elevational view thereof;

FIG. 9 is a right side elevational view thereof;

FIG. 10 is a bottom plan view thereof;

FIG. 11 is a rear elevational view thereof; and

FIG. 12 is a left-side elevational view thereof.
